EXPANSIBLE SECURING DEVICE FOR WATCH-BRACELETS.

1.113,885.

Specification of Letters Patent.

Patented Oct. 13, 1914.

Application filed February 10, 1914. Serial No. 817,745.

REISSUED

To all whom it may concern:

Be it known that we, CHARLES L. DEPOLIER and EDWARD C. DUNCUFF, citizens of the United States, residing in the city, 5 county, and State of New York and Mount Vernon, in the county of Westchester and State of New York, respectively, have invented certain new and useful Improvements in Expansible Securing Devices for 10 Watch-Bracelets, of which the following is a specification.

Our invention relates to novel means for securing a watch, locket, or other suitable useful and ornamental article to the ends of 15 an expansible bracelet.

The main object of this invention is to provide two sliding links at both ends of the bracelet, which links may be easily and readily manipulated so as to increase the size of 20 the bracelet to facilitate its being passed over the hand and on to the wrist and then manipulated so as to bring the bracelet back to its normal size when it may be fastened.

Another object of the invention is to provide an expansible sliding link which includes a hook without the use of a spring, which would increase the size of the bracelet, so as to facilitate the sliding of the bracelet over the hand without unhooking the watch, 25 since as heretofore many bracelets have been damaged or broken apart, owing to the stretching that is necessary to expand the same sufficiently to allow the bracelet to slide over the hand before reaching the 30 wrist, and it is well known that the ordinary expansion bracelet does not possess sufficient expansion to allow the bracelet to readily slip over the hand. Further, our improved hook link permits the watch to be readily 35 detached entirely from the bracelet and to be worn as an ordinary watch.

A further object of this invention is to furnish an expansible link comprising a hook which locks itself, said hook having 40 projections at each side thereof at one end adapted to slide within another link provided with grooved side pieces, said grooved side pieces being connected at one end by a member which covers the end of the hook 45 when the link is closed thereby adding security to the hook and leaving no projecting point to come in contact with the wearing apparel when either opened or closed.

A still further object of the invention is to

provide securing means which can be utilized in any part of the bracelet to furnish the increased expansion, and allow of its being detached thereby separating the bracelet in any part as may be desired by the wearer.

The foregoing and such other objects as may occur from the ensuing description are attained by the construction, combination, arrangement and location of the parts hereinafter more fully described, illustrated in 65 the accompanying drawings forming a part of this specification, and particularly pointed out in the claims appended hereto.

With reference to the drawings:—Figure 1, is a perspective view of an expansible 70 watch bracelet embodying our invention. Fig. 2, is an edge view of a portion of the bracelet showing one end of the bracelet hooked to the watch and the other end detached therefrom. Fig. 3, is a side view of 75 a portion of the bracelet showing the expansible securing means located intermediate the bracelet. Fig. 4, is an edge view of the structure shown in Fig. 3. Fig. 5, is a longitudinal sectional view through our improved 80 securing means showing the hook in full lines. Fig. 6, is a side view of the hook portion of the securing means. Fig. 7, is a top plan view of the structure shown in Fig. 6. Fig. 8, is a side view showing a slightly 85 modified form of a portion of the securing means without the hook, and Fig. 9, is an enlarged front elevation of the forward end of that portion of the securing means which carries the hook.

In the several views of the drawings similar characters of reference are employed to designate like or the same parts throughout where they occur, wherein—

1, designates the links of an expansible 95 bracelet, and 2, the watch to which the bracelet is attached at each end thereof.

By reference to Fig. 1 of the drawings it will be seen that the watch is secured at each end of the bracelet by our improved securing means which consists of an expansible structure without springs and is composed of two pieces or link members, one member consisting of an open hook link 3 separated at an incline to the direction of its 100 length near the forward end thereof to form a hook portion 4, the other end being provided at each side thereof with a projection 105

5, and the upper portion being inclined upwardly and forwardly to form a hump portion 6 for the purpose hereinafter described. The other member 6' of the expandible securing structure consists of two side pieces 7 secured at one end by a pin 8 and at its forward end by a top and bottom piece brazed or otherwise secured together to form an integral end portion 9 substantially 10 as shown in Fig. 9. In each side portion 7 the inner wall is provided with a longitudinal groove 10 adapted to receive the projections 5 thus serving to retain the link 3 between said side pieces, thereby preventing 15 said link from getting out, and acting as a guide for the reciprocal movement of the side pieces, when moved back and forth over the link 3.

The forward upper end portion 9 of the 20 member 6' is so constructed that it allows the hump portion 6 of the hook to pass thereunder, and when member 6' is slid to its forward position said end portion 9 will rest in front of the hump portion 6 and 25 cover the end of the hook thereby closing the hook portion thus adding to its security and leaving no projecting point to come in contact with wearing apparel, hence when the expandible link is closed the hook is 30 protected by the top piece of the member 6'.

In Fig. 8 of the drawings is shown a solid member 11 constituting one portion of the expandible structure, this member 11 being in one piece, the forward end portion 12 being of such a resilient character that by 35 pressing downward on the hump portion 13 the top piece of the member 6' may be readily released and slid in a rearward direction to expand the structure and increase the size 40 of the bracelet.

It will be readily understood that when the parts constituting our improved expandible securing means at each end of the bracelet are in closed position the top piece 45 on the forward end of the member 6' rests in front of the hump portion on the open link hook member 3, and covers the end of the hook and by merely pressing downward on the hump portion member 6' is released and 50 caused to move rearwardly thus opening the structure and materially increasing the size of the bracelet, then by pushing the member 6' in a forward direction until it rides over the hump portion it will snap behind said 55 hump portion thereby closing the hook and reducing the bracelet to its normal size.

It will be observed that by attaching the expandible securing means hereinbefore described to each end of the expandible bracelet, such as shown in Fig. 1, the size of the 60 bracelet can be readily increased in excess

of its normal expansion to facilitate it being readily passed over the hand, and by the closing and locking of said means the added increase in the size of the bracelet is reduced 65 sufficiently to hold the watch snugly on the wrist of the wearer.

It will be perceived that slight changes in the precise details of construction may be resorted to without departing from the spirit 70 of our invention.

Having thus described our invention what we claim and desire to secure by Letters Patent is:—

1. A device for securing a watch to an expandible bracelet at each end thereof, comprising an expandible link structure consisting of two interlocked members slidable in relation to each other, one member being composed of an open link having a resilient 75 upper portion provided with a hump and having a hook at one end, and another member composed of two side pieces connected together at each end, one end having an outwardly projecting portion adapted to slide 80 over said hump and rest in front thereof to lock said hook when the structure is in its contracted position.

2. A device for securing a bracelet together at any intermediate portion thereof, 90 comprising an expandible link structure consisting of two interlocked members slidable in relation to each other, one member being an open link separated on a diagonal line at its forward end to form a hook, and having 95 a resilient upper portion provided with a hump and adapted to open and close said hook, and another member composed of two side pieces connected together at one end and the other end of said side pieces being connected by an outwardly projecting portion 100 adapted to slide over said hump and rest in contact with the front thereof to close and lock said hook when the link structure is in closed position.

3. A device for securing a watch to an expandible bracelet, comprising an expandible link structure composed of two link interlocked members slidable in relation to each other, one member consisting of an open 110 link having a hook at one end thereof and provided with an upper resilient portion, the other member having means at one end thereof for locking said hook and resilient member for the purpose set forth.

In testimony whereof we affix our signatures in presence of two witnesses.

CHARLES L. DEPOLIER.
EDWARD C. DUNCUFF.
